LAG FUSE

Gordon F. Laing, Delavan, Wis., assignor to
Economy Fuse and Manufacturing Co., Chi-
cago, Ill., a corporation of Illinois

Application October 23, 1950, Serial No. 191,627

5 Claims. (Cl. 200—123)

1

The present invention relates to improvements in lag fuses.

More particularly, the present invention relates to the type of electric fuse which will open an electric circuit promptly upon a high surge of current, such, for example, as accompanies a short circuit, but will delay the opening of the electric circuit for predetermined periods upon moderate overloads such as those frequently encountered in motor starting operations.

Though a preferred embodiment of the present invention has been illustrated in a non-renewable fuse of the ferrule type, it will be understood as the description proceeds that the invention is equally applicable to other types of fuse.

An object of the present invention is to provide a lag fuse which is dependable in protecting an electric circuit under conditions approximating short circuit, but will delay for predetermined long periods the opening of the circuit upon moderate overloads.

A further object is to provide a lag fuse of the type just referred to which is relatively simple to manufacture and dependable in service.

A further object is to provide a lag fuse of a relatively high heat capacity whereby moderate overloads may be carried for prolonged periods of time with assurance that the circuit will be opened when a predetermined product of overload and time factors has been reached.

A further object is to provide a lag fuse well adapted to meet the needs of ordinary service.

Other objects will appear as the description proceeds.

Referring to the drawings—

Figure 1 is a longitudinal sectional view illustrating a preferred embodiment of the present invention, the parts being shown in current passing relationship with one another; and

Figure 2 is a view similar to Figure 1, but showing the parts located in positions they will assume when the fuse has operated to break the circuit after the lapse of a predetermined period of overload.

The numeral 10 indicates a tube which according to usual practice may be composed of fiber or the like. Located at the two ends of the tube 10 are the ferrules 11 and 12, which are cup-shaped members closely receiving the ends of the tube 10. Said ferrules 11 and 12 are slotted in their bottom portions to receive extremities of fuse links to be referred to presently. Said extremities of said fuse links are soldered or otherwise electrically connected to said ferrules 11 and 12.

Located within the tube 10 is a fuse assembly indicated as a whole by the numeral 13. Said fuse assembly 13 is composed essentially of the slug heat reservoir 14, the tubular heat reservoir 15, the plunger reservoir 16, portions of low melting point eutectic solder 26a and 26b connecting said reservoirs 14 and 16 and said reservoirs 16 and 15, respectively, the spring 17 and the fuse links 18 and 19, which fuse links comprise heating members for said reservoirs and said portions of solder. The fuse links 18 and 19 are electrically and mechanically united to the slug heat reservoir 14 and to the tubular heat reservoir 15, respectively, in any preferred way. According to the illustrated embodiment of the present invention, the links 18 and 19 have their innermost ends provided with feet which are staked and soldered to the reservoirs 14 and 15, respectively. The links 18 and 19 may take any preferred conformation and will ordinarily be provided with restricted portions 10 and 21, respectively, or a plurality of such restricted portions, according to usual practice.

Located upon and fitting the fuse links 18 and 19, respectively, are fiber washers 22 and 23, which fiber washers together with the two ferrules 11 and 12 provide chambers 24 and 25, respectively, at the two ends of the fuse for receiving quenching powder. Between the two washers 22 and 23 is the chamber 26 receiving the slug heat reservoir 14, the plunger reservoir 16, the tubular reservoir 15, together with the spring 17, and the two portions 26a and 26b of low melting point eutectic solder for holding said reservoirs in series relationship against the tension of said spring.

The plunger reservoir 16 has the head portion 27 and the shank portion 28, which shank portion fits loosely within a corresponding hole in the tubular reservoir 15. The fit between the shank portion 28 and the tubular reservoir 15 should not be so close that compressed air will retard the movement of said shank 28 into said tubular reservoir 15.

The plunger reservoir 16 is urged toward the right as the parts are viewed in the drawing by the spring 17, the left hand convolutions of which are threaded onto a corresponding groove in the head portion 27 of said plunger reservoir 16. The outer diameter of the tubular reservoir 15 is of a size to receive the coil spring 17. Said tubular reservoir 15 at its right hand end is provided with an end portion 29 of reduced diameter, providing a shoulder for receiving the right hand end convolution 30 of the spring 17. In other words, the

shoulder at the right hand end of the tubular reservoir 15 is abutted by the end convolution 30 of reduced diameter of the spring 17, the net effect being that the spring 17 urges the plunger 16 into the tubular reservoir 15 and away from the slug heat reservoir 14.

The mode of operation of the above described embodiment of the invention will be clear without detailed explanation. When the fuse is located in an electric circuit, said fuse will protect such circuit against conditions approximating short circuit for the reason that the fuse links 18 and 19 will fuse in the manner well understood under such short circuit conditions.

Under overload conditions the fuse links 18 and 19 will warm up, acting as heaters communicating heat to the members 14, 15 and 16, which, being heat reservoirs, will store up such heat to a predetermined extent, depending jointly upon the degree of overload and the prolongation of the period of overload. The melting point of the eutectic solder uniting the plunger reservoir 16 to the heat reservoir 14 and the tubular reservoir 15 may be accurately predetermined; and when sufficient heat has been stored in the members 14, 15 and 16 to melt this eutectic solder, the spring 17 will move the plunger reservoir 16 to the right, effectually opening the circuit between the slug heat reservoir 14 and the plunger reservoir 16, thereby opening the electric circuit.

Though a preferred embodiment of the present invention has been described in detail, many modifications will occur to those skilled in the art. It is intended to cover all such modifications that fall within the scope of the appended claims.

I claim:

1. Fuse construction comprising a casing, partitions in said casing dividing it into end and central compartments, fuse links in said end compartments each extending between the adjacent casing terminal and the proximate partition into the central compartment, the terminus of each link in the central compartment being in spaced relation to the opposite link terminus therein; a relatively massive metallic conductor of large thermal capacity bridging and connecting the link terminals in the central compartment, said massive conductor being formed in three parts: one part of which is connected in permanent mechanical and electrical union with the terminus of one fuse link; an opposite part which is similarly connected to the opposite fuse

link terminus in spaced relation to said one part, and a connecting part in telescoping engagement with said one part and joined to it and to said opposite part by low melting point solder; and

5 a spring extending under tension between the telescoped parts when the three parts are soldered together so as to bias the connecting part away from said opposite part.

2. The fuse construction specified in claim 1, in which said spring is a helical spring within the bore of which said telescoping parts are accommodated, one convolution of said spring being sufficiently reduced in diameter to engage an axial bearing on one of said telescoping parts, the other of said telescoping parts having screw-threads complementary to the convolutions of said spring which are screwed into engagement with the latter when telescoped relative to the other part.

3. The fuse construction specified in claim 1, in which the end chambers of said casing are filled with quenching powder in which said fuse links are embedded.

4. A lag fuse assembly comprising, in combination, a pair of fuse links in spaced relation, a relatively massive metallic conductor of large thermal capacity permanently connecting said free links in bridging relation, said massive conductor being in three parts, two of said parts being constructed and arranged to slide axially of each other into and out of abutting relation to the third part; and a helical spring tending to withdraw said sliding parts from abutment with said third part, and low melting point solder holding said three parts in abutting relation.

5. The lag fuse assembly specified in claim 4, in which said helical spring has convolutions at one of its ends in screw-threaded engagement with one of said sliding parts, and a constricted convolution at its opposite end bearing upon a portion of reduced diameter on the other sliding part, said parts being coaxial with said spring and with each other.
